UNITED STATES PATENT OFFICE.

SIMON MATZNER, OF NEW YORK, N. Y.

SURFACE PROTECTOR.

Application filed May 18, 1925. Serial No. 31,184.

To all whom it may concern:

Be it known that I, SIMON MATZNER, a citizen of the United States of America, and resident of the city of New York, borough of Manhattan, in the county of New York and State of New York, have invented a new and Improved Surface Protector, of which the following is a full, clear, and exact description.

10 This invention relates to surface protecting devices constituting an improved means carried by a supporting base for preventing the scratching or marring of the surface upon which the base sets.

15 At the present time the supporting bases of lamps, telephones, smoking stands or other similar articles are usually of hollow construction presenting an annular bead or rim within which a felt covered pad element 20 is received and from which the same partially projects to provide a padded surface protecting means for the base. In practice it has been found that such means in addition to the expense and labor involved in 25 their production and association with the bases are open to the objection that they collect dust, dirt and grit and require in a short period of time renewal due to the fact that their wearing qualities are not of the 30 highest.

It is therefore an object of the present invention to provide a surface protecting means for attachment to a base which in addition to performing its function in a better and more facile manner, renders the device less expensive in its production and association with the base while materially increasing its length of usefulness.

With the above recited and other objects 40 in view, reference is had to the following specification and drawings in which there is exhibited one example or embodiment of the invention which is in no way intended as a limitation upon the scope of the appended 45 claims as it is to be clearly understood that variations and modifications which properly fall within the scope of said claims may be resorted to when found expedient.

In the drawings—

50 Figure 1 is a vertical sectional view through a portable fixture base equipped with a surface protecting device constructed in accordance with the invention.

Fig. 2 is a bottom plan view thereof.

Referring to the drawings by characters 55 of reference A designates a base of hollow formation which produces the usual depending annular rim or bead B. In lieu of inserting and securing within the lower open end of the base a felt covered member under 60 the common practice, a strip 10 conforming substantially to the side and configuration of the interior of the rim is employed which is covered with a tubular yieldable material 11 snugly fitted thereover. Preferably the 65 strip 10 is of a resilient or spring material and the tubular covering 11 of rubber or a material having the characteristics of rubber. The covered strip is positioned within the rim B with one of its edges projecting 70 below the lower edge of the rim or bead B and the same is preferably held and maintained in such position by means of a plurality of screws 12 which extend transversely through the strip and its covering and 75 threaded engaged in threaded openings 13 in the strip 10. The screws are provided at their inner ends with kerfs 14 and at their outer ends with pointed terminals 15 which are adapted to bite into the inner surface 80 of the rim or bead B thereby preventing relative turning or axial movement of the surface protector with respect to the bead. It is of course understood that in circular bases the strip 10 will assume the general shape 85 of a split ring while in noncircular bases the strip conforms to the shape or configuration of the base.

From the foregoing it will thus be seen that an extremely simple yet highly efficient surface protector has been provided which may be manufactured cheaply and which may be connected or associated with the base in a minimum time. It is also obvious 90 that the device when its lower wearing edge 95 is worn may be removed and inverted thereby doubling the length of life or usefulness of the same.

I claim:

1. The combination with a supporting 100 base having a depending marginal rim, of a surface protecting device for preventing the scratching or marring of the surface upon which the base rests, comprising a resilient strip of material, a tubular yieldable covering thereover, radially adjustable elements extending through the strip and covering 105 and pointed terminals at the outer end of

said elements adapted to bite into the inner periphery of the rim for maintaining the strip in place with the thickness of the covering projecting beyond the lower edge of the rim.

2. The combination with a supporting base having a depending marginal rim, of a surface protector therefor comprising a split metallic strip of resilient material conforming substantially to the configuration of the rim, an elastic tubular covering fitted over

said strip, set screws having pointed outer terminals extending through the strip and covering and threadedly engaging the strip for effecting a biting engagement of the 15 pointed terminals with the inner face of the rim to removably maintain the protector in place against circumferential or axial movements and to permit of the reversal thereof when the surface contacting portion is worn.

SIMON MATZNER.
